UNITED STATES PATENT OFFICE.

WILLARD P. FOWLER, OF METROPOLIS, ILLINOIS.

AUTOMATIC RAILWAY SIGNALING DEVICE.

Application filed September 8, 1925. Serial No. 55,107.

This invention relates to signaling systems, and especially to an improved automatic railway crossing signal.

One object of this invention is to provide a railway crossing signal which automatically operates to announce the approach of a car or train on a railway track, to retain one or more signaling elements in the signaling position until the car or train has entirely passed the crossing and the signaling element, then automatically moves the signaling element into a position for indicating the fact that the train has passed, or out of the above mentioned signaling position.

A further object of this invention is to provide an improved mechanically operated and electrically controlled device for operating a railway gate or other signaling element so as to move such signaling element from a vertical position to a horizontal position, and vice versa, such electro-mechanical device being entirely automatic; that is, entirely dependent upon the approach and departure of a car or train, for starting and stopping and reversing the mechanical elements which operate the signaling element.

Another object of the invention is to provide a device of this character having all its parts united, except the railway and its electrical connections, or consisting of a unitary combination which is capable of being carried bodily, thereby avoiding the necessity of building the device at the place it is to be installed at a railway crossing.

Another object is to provide a device of this character which consists of comparatively few and very strong and durable parts, thus providing the maximum service and efficiency at a comparatively low cost of installing and maintaining the device.

Other objects and important features are pointed out or implied in the following details of description, in connection with the accompanying drawings in which:

Fig. 1 is a view mainly in side elevation, but partly in vertical section, and partly diagrammatic, certain parts being broken away for showing other parts, and for lack of sufficient space to show some of the parts in their entirety:

Fig. 2 is a top plan view of one end of the main actuating bar; and,

Fig. 3 is a diagrammatic view of the electrical system which operates and controls the mechanism for raising and lowering the

pole, paddle or gate which constitutes the signaling element above referred to.

It is generally and well known that a paddle or pole which is extended across a wagon-road (this term to distinguish from a railroad) is intended more particularly to warn the drivers of wagons and other vehicles, as well as pedestrians and equestrians, rather than actually making it impossible for them to cross the railroad, pedestrians often cross in spite of a warning given by the signal. Therefore, the bar or paddle here operated as a gate is, in its broadest sense, a signaling element, and will hereafter be referred to as such. This gate or signaling element is here referred to or designated by the numeral 5, and a sufficient portion of it is here shown to make clear its operation. It is shown in full lines in its horizontal position, and in broken lines in its vertical position. It is clamped or otherwise secured on a stud or stub shaft 6 which is journaled in an upright frame element 7, the latter being secured on a base 8, which latter also supports other upright frame elements which will presently be described. A shaft 9 is also journaled in the upright frame element 7, and this shaft carries a gear wheel 10 which meshes with a gear wheel 11 on the stub shaft 6. The shaft 9 also carries a segmental gear 12 which meshes with a worm 13. This worm is secured on a shaft 14 which is journaled in suitable bearings on the upright 7 and on a somewhat similar upright 7^a. Beveled gear wheels 15 and 16 are formed integrally with or united with annular clutch elements 15^a and 16^a. Each of these gear wheels is rotatable with its contiguous clutch element around the shaft 14, being journaled on the latter. A pair of clutch levers 17 is provided for each of the clutch elements 15^a and 16^a, each of these clutch levers 17 being provided with a friction-element 18 and with an adjusting screw 19. A sleeve 20 is feather-keyed or otherwise secured against rotation on the shaft 14, and has inclined ends on which the adjusting screws 19 slide for swinging the lever 17 of each pair so as to bring the friction-elements 18 into frictional engagement with the clutch-element 15^a or 16^a. The middle part of the member 20 is provided with an annular groove 21 in which a stud 22 extends from a lever 23 which is pivoted on an upright 24 and has a slot 23^a in its upper end.

100

105

110

A beveled gear wheel 25 is mounted on a shaft 26 and is continually in mesh with the beveled gear wheels 15 and 16. A worm-gear-wheel 27 is also secured on the shaft 26 and serves as a driving wheel for the gear-wheel 25. This wheel 27 is driven by a worm 28 which has its shaft 29 journaled in suitable bearings on the base 8. The shaft 29 is driven by an electric motor 30 which may be of any appropriate kind or type.

A main actuating bar 31 is provided with a slot 31^a, and a doubleheaded pin or bolt 32 extends through the slots 23^a and 31^a so as to operatively connect the lever 23 with the bar 31 for a purpose which will hereafter be explained. A link 33 is pivotally connected to the bar 31 and to a supporting element 7^b which is secured on the upright 7^a. A link 34 is also pivotally connected to the bar 31, preferably by the same pivot 31^b which connects the link 33 to the bar 31. A contractile spring 35 has its upper end secured to the link 34, and has its lower end secured to an element 36 on the base 8. This spring holds the bar 31 alternately in the broken line positions 31^A and 31^B, and also forces this bar to either of said broken line positions when it has passed slightly beyond its neutral position which is shown in full lines; that is, when the link 33 has passed slightly beyond its vertical position, or carried its pivot 31^b beyond the plane which is common to the fixed pivot of the link 33 and the fixed connection of the spring 35. The bar 31 rests upon the upper end 7^c of the upright 7^a when said bar is in either of its positions 31^A and 31^B. It will be seen that when the bar 31 moves rightward to the position 31^A, it swings the lever 23 for rendering the clutch levers 17 effective for securing the gear wheel 16 against rotation on the shaft 26; that is, it locks the gear wheel 16 to the shaft 14 so that when the gear wheels 25 and 27 move in the direction of their respective arrows, they turn the shaft 14 in the direction of the curved arrow shown thereon. This turns the worm 13 in the direction for turning the segmental gear 12 in the direction of its arrow. An arm 37 is either clamped on a hub of the gear segment 12, or secured to the shaft 9 by any appropriate means, and this arm is connected by a link 38 to a lever 39 which is pivoted at 40 to a bearing secured on an insulated platform 41, the latter being supported by the upright frame element 7. The lower end of the lever 39 is pivotally connected to a link 42, and the latter is pivotally connected to a lever 43 which is pivotally mounted at 44 on the base 8. The letter *a* and the adjacent broken line indicate the plane of the pivots of the lever 43 when near its extreme leftward position of Figure 1, and the letter *A* indicates the

plane of such pivots near the extreme rightward position of the lever 43. Similarly the broken line at *b* indicates the plane coinciding with the center of the spring 35 and link 34 when they are near their leftward position, and the broken line *B* indicates the plane coinciding with the centers of the elements 34 and 35 when near their extreme rightward position.

A single pole double throw switch 45 is pivotally mounted at 46 on the insulated platform 41, and this switch includes two contacts 47 and 48. This switch will herein-after be referred to as the S. P. D. T. switch. Its upper end is provided with a slot 45^a through which a stud 49 extends from an arm 50 which is pivotally connected at 51 on the bar 31. The upper end of the lever 43 is in the path of two spaced abutments 52 and 53 of the bar 31, so that such abutments are engaged by the lever 43 for moving the bar 31 from the positions 31^A and 31^B to the full line position or slightly past the full line position shown in Figure 1; and when the bar 31 has moved slightly past its full line position, in either direction, the link 34 and spring 35 cooperate in completing the movement of the bar 31 to one or the other of its broken line positions. It will be understood that the lever 43 is moved by the previously described gearing and the system of arms, links and levers 37 to 42 inclusive, and that the space between the abutments 52 permits the bar 31 to complete its movement to the 31^B position, for instance, while the lever 43 remains near its *a* position.

It will be understood, from the foregoing, that the S. P. D. T. switch is also operated by the bar 31, this being accomplished through the medium of the arm or link 50 and its stud 49; and now, it may be well to review the structure thus far described and to explain a cycle of its operation as follows: Assuming that the signaling element 110 has been moved from its upright or broken line position to its horizontal or full line position by the gearing mechanism previously described, the clutch levers 17 (at the right) being in the effective position 115 shown, so that all parts having arrows thereon are moving in the direction indicated by said arrows, and have so moved until the link 33 has its pivot in the same plane with the spring 35, the connecting stud 32 having just engaged with the right-hand end of the slot 31^a, and the stud 49 having just engaged with the left-hand end of the slot 45^a in the S. P. D. T. switch, the latter being closed with the contact 48 and being open with respect to the contact 47. Now, when the gearing continues its movement slightly, for bringing the arm or paddle 5 to the end of its downward movement, such movement of the gearing and system 130

of levers and links moves the bar 31 leftward slightly beyond the full line position, so that the spring 35 and link 34 now quickly shift the bar 31 to the position 31^b, and 5 in doing this, the S. P. D. T. switch is opened at 48 and closed at 47. In the operation of thus shifting the S. P. D. T. switch, it is momentarily open at both 47 and 48, which breaks the circuit for a purpose which 10 will presently be explained. Another function of the bar 31, during its quick change from the full-line position to the broken line position 31^b, is to shift the lever 23 leftward sufficiently far to move the clutch 15 sleeve 20 out of engagement with the screws 19 of the clutch levers which co-act with the clutch element 16^a, and into engagement with such screws of the clutch levers which cooperate with the clutch element 15^a, thus 20 leaving the bevel-gear-wheel 16 free to turn on the shaft 14, at the same time locking the bevel-gear 15 on the shaft 14, so that when the gear wheel 25 continues or resumes its movement in the direction of its arrow, the 25 shaft 14 will be turned in the direction opposite to that which is indicated by its arrow, and accordingly, the parts 37 to 42 inclusive, will move in the direction opposite to that indicated by their respective 30 arrows. Such movement of these parts 37 to 42, inclusive, swings the lever 43 rightward, and the same, now being against the abutment 53, moves the bar 31 rightward until it reaches the full line position here shown. 35 However, it is to be remembered that the S. P. D. T. switch is now in its broken line position, and the lever 23 is in its leftward position, its stud 32 being in the left end 40 of the slot 31^a; and now, when the bar 31 has brought its stud or pivot 31^b slightly to the right of the position here shown, the spring 35 and its link 34 now bring the stud 31^b into the plane indicated by the broken line B. During this reverse movement of 45 the gearing and combination of links, levers, etc., the paddle or signal element 5 has moved to and slightly beyond the broken line position thereof.

Now, referring to Fig. 3, in which the motor 30 and the S. P. D. T. switch 45—47—48 are the only elements described in the foregoing, I will explain the electrical system which controls the motor 30 and is controlled by the S. P. D. T. switch, as follows: 55 At 60 is indicated an electric generator, and it is understood that any form of generator may be employed in connection with the power circuit indicated at 61. In practice, such power circuit may consist of telegraph wires which are usually adjacent to railroad tracks. A railroad track is indicated at 62, 63 and 64, each of these reference characters indicating a section of track which is separate from the other sections, 60 that is, the track sections 62 and 64, al-

though electrically connected to one another, are not electrically connected to the track section 63 nor to the distant parts of the railroad; but these sections are aligned and in close relation to one another so that 70 a car or train can pass from each section to the other section as if these track sections were integrally united. The track sections 62 and 64 are electrically connected by conducting wires 65 and 66. Conducting wires 75 67 and 68 are connected to the respective rails of the section 62, and a battery 69 is included in the conductor 68. A relay 70 has its terminals connected to the conductors 67 and 68, and this relay has a pivotally mounted arm 71 to which is connected a conductor 72 which terminates in a contact 73 on said arm, the other end of said conductor being connected to a rail of the section 63. The arm 71 is connected to the 80 switch contact 48 through the medium of a conducting wire 74 which terminates in a contact 75 on said arm. On a supporting extension of the relay 70 are two contacts 76 and 77 in position for closing the circuit 85 with the contacts 75 and 73 respectively.

A relay 78 is connected by a conductor 79 to the opposite rail of the section 63, that is, to the rail opposite that to which the conductor 72 connects. This conductor 79 90 has an extension 79^a which terminates in a contact 80 on an extension of the relay 78. The other terminal of the relay 78 is connected to the same rail to which the conductor 72 is connected, a conductor 81 being the medium through which this rail is connected to the relay 78. The conductor 81 includes a battery 82.

An arm 83 is pivoted on the relay 78 and carries a contact 84 on one side, and a contact 85 on its opposite side. An extension of the relay 78 carries a contact 86 in position to close circuit with the contact 85. A conductor 87 connects the contacts 76 and 86 to one another. A conductor 88 connects the contacts 77 and 84 to one another. A conductor 89 connects the contact 85 with one of the conductors of the power circuit 61, and this conductor is also electrically connected to a conducting element 90 on which is pivoted a conducting arm 91 which has thereon a contact 92. A contact 93 and a conducting wire 94 connect with the contact 47 of the S. P. D. T. switch. A breaking relay 95 has one of its terminals connected by a conductor 96 to the contact 48 of the S. P. D. T. switch, through the medium of the conductor 74 or through other proper means. The other terminal of the relay 95 is connected, by a conductor 97, to one of the power conductors 61, that is, to the one opposite to that which connects to the conductor 89. A conductor 98 connects one terminal of the motor 30 to the conductor 97. A conductor 99 connects the other ter- 100 105 110 115 120 125 130

50 minal of the motor to the movable part 45 of the S. P. D. T. switch.

55 The above described electric system includes five electric circuits, all of which are co-operative, and some of which include elements of other of these circuits: In the first place, there are two interdependent motor-circuits or power-circuits; the first including the generator 60, and conducting elements 61, 89, 85, 87, 76, 75, 74, 48, 45, 99, 30, 98 and the part of 97 that connects to one of the conductors 61; the second including conducting elements Nos. 60, 61, a part of 89, 89^a, 90, 91, 92, 93, 94, 47, 45, 99, 30, 98, and 15 the part of 97 that connects to one of the conductors 61. The third circuit may properly be termed the primary track-circuit or automatic closer for the motor-circuits, and it includes the track-sections 62 and 64, their bonding conductors 65 and 66, the other conducting elements indicated at 67 to 70, inclusive, and the wheels and axles of a car or train on either of these track sections. The fourth circuit is for cutting out the 20 motor or breaking the motor-circuit when the motor has moved the signal element 5 to its lowered or signaling position; it includes a shunt connected to the conductors 74 and 97, and this shunt includes the relay 95 and the conductor 96. The fifth circuit may be termed the holding circuit, for it holds the motor circuit open at the circuit-breaking connection 85—86 while it is held closed at the circuit-breaking connection 75—76 during the time the car or train is on either track-section 62, or 64. In this connection, it should be understood that the rails of these track-sections are bonded for a fraction of a mile from the section 63 and 30 signaling element 5, and that beyond such fraction of a mile, these bonded sections terminate, and the continuation of the railroad is not electrically connected to these sections.

45 When the machine is not in operation, and the arm or member 5 is up, or when such arm is on its way down to the signaling position, the S. P. D. T. switch-element 45 is in closed relation with the contact 48 which 50 may be termed the lowering contact; but when the member 5 is at its lowest or signaling position, or rising therefrom, the element 45 is closed with the contact 47 which may be termed the raising contact.

55 The operation of this electrical system is as follows:

60 Assuming that the signaling member 5 is up, and that the track-circuit is closed or completed by wheels and axles 101 of a car or train, this starts a current through the battery 69, thereby energizing the relay 79, thus moving the contacts 73 and 75 into closed relation with contacts 77 and 76 (respectively). This closes one of the breaks 65 in the holding circuit and fully closes the mo-

tor-circuit first-described in the foregoing; so the motor now starts to lower the signal-element 5, and continues until the signal-element is lowered and the switch-element 45 is shifted into closed relation with the contact 47, as previously described. The current from the generator 60 can not now go through the second-described circuit, because it is held open, at 92—93, by the breaking relay 95, so the motor 30 stops, and the signaling element 5 remains down until the motor again starts. Now, remembering that the switch-element 45 has shifted to the raising contact 47, and assuming that the wheels and axles 101 have now passed from the section 62 to the sections 63 and 64, it will be seen that the relay 70 remains energized while the relay 78 becomes energized in consequence of the completion of the circuit through the battery 82; so the relay 78 now causes its arm 83 to break contact at 85—86, so that the current is cut off from the breaking relay 95, and the spring 100 causes the arm 91 to close the second-described circuit including the motor 30, and the motor now begins again to operate and continues until the switch-member 45 is shifted from the raising contact 47 to the lowering contact 48. Now, to prevent the first-described motor-circuit from being closed when the car or train has left the section 63, but still on either section 62 or 64, and thus prevent untimely lowering of the gate or signal-element; the above-described holding circuit is held closed at 80—84, by the battery 82 energizing the relay 78, and stays closed (while holding the motor-circuit open) until the above-described closing circuit is opened by the car or train passing from the section 62 or 64, whereupon the battery 69 ceases to energize the relay 70, so both the motor-circuit and holding circuit are now opened at 75—76 and 73—77, and the motor remains out of circuit with the generator until the track-circuit becomes again closed by an approaching car or train on either track-section 62 or 63. It is not intended to limit my patent-protection to the exact details of construction and arrangement here shown, for the invention includes numerous equivalent forms, substantially as claimed.

55 What I claim as my invention is:

1. In a railway signaling system; the combination of a signaling member; a reversible gearing operable to move the signaling member to and from its signaling position; gearing mechanism to drive said reversible gearing; two interdependent electric currents having a normally open part and including a motor for driving said gearing mechanism, a double throw switch which includes two contacts and a movable element, the latter being electrically connected to one terminal of the motor and alternately connectable with said contacts, electric conductors electrically 125

- connected to the other terminal of said motor, an electric generator to which said terminals of the motor are electrically connected, means to shift said switch for breaking 5 with one of its contacts and closing with its other contact, circuit-breaking means automatically operable to break the circuit through the motor upon thus shifting said switch; and an incomplete closing circuit 10 including a circuit-closing relay, two railway rails, a battery, and conductors connecting said relay and battery and railway rails in series, this closing circuit being adapted to be completed by a conducting axle and 15 wheels on said railway rails and thus made effective for closing said normally open part of the said interdependent circuit.
2. In a railway signaling system; the combination of a signaling member; a reversible 20 gearing operable to move the signaling member to and from its signaling position, gearing mechanism to drive said reversible gearing; and a system of electric conductors including the following; viz, a non-reversing 25 electric motor operable to drive said gearing mechanism in only one direction, a generator electrically connected to said motor for driving the latter, two interdependent electric circuits connected in parallel with 30 the electric connections between the generator and motor and including a normally open circuit breaking part, a double-throw switch operable by said gearing mechanism for closing said normally open part and 35 breaking the circuit at another part, a shunt including a relay for breaking the circuit at another part when said double throw switch closes said normally open part, said interdependent circuits including a second 40 normally open circuit-breaking part; a railway-section, means operable by rolling stock on the railway-section for closing said second normally open part of the interdependent circuits, this last said part being effective, 45 when closed, for completing the circuit through said shunt and thereby energizing its relay, said interdependent circuit including a normally closed circuit-breaking part, and an incomplete electric circuit including 50 a relay and adapted to be completed by said rolling stock and to actuate its relay for breaking said normally closed part; for the purposes specified.
3. An electric system including a motor, 55 and means for starting and stopping the motor, as follows: viz; electric current supplying conductors connected to the terminals of the motor; two interdependent electric circuits connected in parallel with the said 60 terminals and including three normally closed circuit-breaking parts and two normally open circuit-breaking parts and also including a relay for opening one of these normally closed parts; mechanical means 65 operable by said motor for closing one of said manually open parts and opening the second one of said normally closed parts; a railroad; means operable by rolling stock on the railroad for closing the second one of said normally open parts, and means operable by said rolling stock for opening the third one of said normally closed parts, the electric connections of said second normally open part and said relay being effective to energize the latter upon closing of said 70 second normally open part.
4. A signaling mechanism including a signaling element, a supporting frame on which said signaling element is journaled, a spur-gear on the journal of said signaling element, 75 a second spur-gear of larger diameter than the first said spur-gear and meshing with the latter, an axle journaled in said frame and carrying the second said spur-gear, a worm-gear on said axle, a second axle journaled in said frame and carrying a worm in mesh with said worm-gear, two beveled gear 80 wheels journaled on said second axle, a clutch-mechanism on said second axle and operable to secure said beveled gear wheel 85 alternately to said axle for rotation with the latter, a third axle journaled in said frame, a beveled gear wheel on said third axle and meshing with said two beveled gears, a worm wheel on said third axle and rotatable 90 with the beveled gear on the latter, a worm in mesh with the second said worm gear and provided with means to rotate it, and means 95 connected with the first said axle for actuating said clutch, substantially as described, 100 for the purpose specified.
5. The structure defined by claim 4, the means for rotating the second said worm being electrically operated, and an electric system including a circuit breaking means on said frame and being effective for stopping and starting the electrically operated worm-actuating means, and means operable by the clutch-actuating means for controlling said circuit-breaking means.
6. In a signaling mechanism, the combination of a frame, a signaling element journaled in said frame, a train of gearing operable to turn said signaling element on its journal, an axle journaled in said frame and carrying one of the gears of said train, beveled gears journaled on said axle, a clutch mechanism on said axle and operable to secure the beveled gears alternately to said axle, a second train of gears including a beveled gear meshing with the first said beveled gears, a driving means for actuating said second train of gears, a clutch-controlling bar provided with means operatively connecting it with said clutch mechanism for shifting an element of the latter, a link having one end pivoted on said frame and its other end pivoted to said clutch-controlling 110
- 115
- 120
- 125

bar, a contractile spring connected to said frame and connected to said clutch-controlling bar adjacent to its connection with said link, the latter being normally in an inclined 5 position, and means operable by the first said train of gearing for moving said clutch-controlling bar longitudinally and thereby moving said link into a vertical position and slightly beyond said vertical position, said 10 spring being effective to continue such movement of the clutch-controlling bar and its link for quickly shifting the clutch-element

to which said clutch-controlling bar is operatively connected.

7. The structure defined by claim 6, said 15 driving means being electrically operated and constituting an element of an electric system which also includes a circuit-breaking device for stopping the electrically operated driving means, and means operable by 20 said clutch-controlling bar for controlling said circuit-breaking device.

In testimony whereof I affix my signature.
WILLARD P. FOWLER.
